Primary Examiner — Barbara Fox*Assistant Examiner* — Dana K Weiland(74) *Attorney, Agent, or Firm* — Kilpatrick Townsend & Stockton LLP(57) **CLAIM**

The ornamental design for tablet learning device, as shown and described.

DESCRIPTION

FIG. 1 is a front elevation view of a tablet learning device showing our new design;

FIG. 2 is a back elevation view thereof;

FIG. 3 is a left side elevation view thereof;

FIG. 4 is a right side elevation view thereof;

FIG. 5 is a bottom elevation view thereof;

FIG. 6 is a top elevation view thereof; and,

FIG. 7 is a perspective view thereof.

The broken lines shown in the drawings represent portions of the tablet learning device that form no part of the claimed design.

1 Claim, 5 Drawing Sheets(56)
